GAME

Lawrence Quinn, Oil City, Pa.

Application April 16, 1937, Serial No. 137,353

8 Claims. (Cl. 273—93)

My invention relates to an improved game mechanism, and more particularly to a game mechanism with which games such as baseball and mushball can be played.

5 Accordingly, it is an object of my invention to provide an improved game board upon which can be realistically reproduced the playing field of a game such as baseball and upon which the game can be played in a manner closely simulating that 10 of actual play.

It is another object of my invention to provide a novel game mechanism for the playing of a game such as baseball which will, during the course of play, reproduce all the plays possible 15 in an actual game and in approximately the same frequency of occurrence as takes place in actual play.

It is a further object of my invention to provide a novel game mechanism, such as that for the 20 playing of a game of baseball, in which the element of chance is utilized to select the various plays possible in an actual game for reproduction in the game being played.

Still another object of my invention is to provide 25 a game mechanism which utilizes a novel combination of spinning disk or other rotating member and electrical means to mutually select and designate a play possible in an actual game for reproduction in the playing of the game.

30 A still further object of my invention is to provide a novel game mechanism for the playing of a game such as baseball in which a spinning disk is used to designate a play that might occur in an actual playing of the game and in which electrical means operated by the spinning of the disk are utilized to amplify, modify or clarify the play indicated by the disk.

A further object of my invention is to provide 40 a novel game mechanism for the playing of a game such as baseball in which a rotating disk carries upon its face the designations of a plurality of plays which may occur in the actual playing of the game and in which electrical means, such as lights placed about a reproduction 45 of the playing field and illuminated by the rotating disk, are associated with play designations complementary to those appearing on the disk.

50 Another object of my invention is to provide a game board with novel electrical circuits and means for opening and closing these circuits actuated by a rotating disk to illuminate lights placed about a playing field marked on said board for the purpose of designating, modifying or clarifying

ing the play designated by the position in which the rotating disk comes to rest.

A further object of my invention is to provide a game mechanism embodying novel means for rotation of a disk bearing designations of a plurality of plays one of which is to be selected by chance each time the disk is operated.

A further object of my invention is to provide a game mechanism of the character described with novel means for recording past plays such 10 as the number of strikes, balls, outs, runs and the like.

A still further object of my invention is to provide a novel chance element for game mechanisms of the type to be described which will be actuated by the rotating disk and may modify the play as indicated by the disk.

Another and still further object of my invention is to provide a novel game mechanism of the type to be described in which some or all of the 20 lights arranged about the playing field may have a double feature use of both indicating a play and the positions of players.

Other and further objects of my invention will appear upon consideration of the detailed description of the embodiment of the invention which follows.

In the drawings, wherein like reference characters indicate like parts throughout the several views:

Fig. 1 is a perspective view of one form of game board embodying the present invention in which the various elements thereof are shown in their related positions;

Fig. 2 is a plan view of a portion of the surface of the game board shown in Fig. 1 with the rotating disk removed to show the arrangement of the electrical contacts thereunder and the positioning of the chance elements;

Fig. 3 is a plan view of one type of rotating 40 disk member with the plays possible in an actual game designated on its face separated by solid and dotted lines for a purpose hereafter to be described and showing the relative positions of the contact arm on its under surface;

Fig. 4 is a section through a portion of the game mechanism of Fig. 1 taken substantially on the line 4—4 showing one embodiment of the novel rotating means and bearing for the rotating disk and illustrating the relative positions of the contact arm and electrical contacts under the rotating disk;

Fig. 5 is a view of the under surface of the embodiment of the game board shown in Fig. 1 diagrammatically indicating the electrical circuits 55

utilized in the playing of the game and showing the novel means utilized for rotating the disk;

Fig. 6 is a cross sectional elevation through any one of the lights having a double use showing the novel arrangement of the common ground plate and leads to the filaments;

Fig. 7 is a cross sectional partially exploded view of the novel switching mechanism for indicating the players on base as seen at right angles 10 to its axis of rotation;

Fig. 8 is a view of the mechanism of Fig. 7 as seen along its axis of rotation with the face plate removed;

Fig. 9 is a cross sectional partially exploded 15 view of the novel switching mechanism for indicating plays in the game such as balls, strikes, and outs as viewed at right angles to the axes of rotation of the switching elements; and

Fig. 10 is a view of the mechanism of Fig. 9 20 as seen along the axes of rotation of the switching elements with the face plate removed.

Although my invention may be utilized in the playing of many types of games, it will be described as a game of baseball with a view to clearly and distinctly indicating the subject matter of my invention.

Referring now to Fig. 1, the numeral 10 indicates a suitable surface member for the game mechanism supported by the frame 11 and legs 30 12. Upon surface member 10 is reproduced, as at 13, a miniature baseball diamond. Upon and around diamond 13 is disposed a plurality of lights 14. Lights 14 are marked upon the bulbs themselves, or, as in the embodiment illustrated, 35 upon the surface member 10 adjacent the lights, to indicate the play or modification of the play that will be used in the playing of the game when any particular light is illuminated. Adjacent diamond 13, and mounted for rotation relatively 40 to surface member 10, is a disk 15 bearing upon its surface as at 16 (Fig. 3) designations of the various plays possible in an actual game of baseball.

It is to be noted that the designations of the 45 various plays on the disk are separated by solid and dotted lines for a purpose hereafter to be described.

Mounted adjacent rotating disk 15 on surface member 10 are a fixed play designating pointer 50 17, and a past play indicator switch actuators 18.

Mounted in or upon surface member 10 and semi-circularly arranged under rotating disk 15 are a plurality of contact points 20 (see Figs. 2 and 4) adapted to be successively engaged upon 55 rotation of the disk 15 by the downwardly turned ends of a pair of diametrically opposite contact arms 21 mounted on the under surface of disk 15 as at 22. Contact points 20 are suitably insulated from one another as by mounting or embedding them in an insulating medium 23. Each 60 contact point 20 is connected by suitable circuits to one or more of the lights 14 in combinations as desired. Electrical energy is supplied to these several circuits from any usual source of supply 65 such as an outlet 25 from which current is taken to a transformer 26 (Fig. 5). From one pole 27 of the secondary winding of transformer 26 current is conducted by any suitable circuit to the bearing of the rotating disk 15 and thence to the 70 contact arms 21 in the manner next to be described. Contact arms 21 engaging the contact points 20 close one or more of the circuits to one or more of the several lights 14. The several lights 14 are mounted in a common grounding plate 28 (Fig. 6) which is insulated from frame 11

by insulators 28' and in turn is connected to the other pole 29 of the secondary of the transformer 26 to complete the several circuits.

Figs. 2, 4 and 5 show the novel means used to rotate disk 15 and to complete the circuit between the transformer 26 and contact arms 21. In these figures 30 is a cross member fastened to the frames 11. Affixed thereto as by bolts 31, but insulated therefrom, is a bearing member 32 adapted to receive the end of a shaft 33. Shaft 33 10 passes through a bearing 34 in the insulating medium 23 of surface member 10. Keyed to the top of shaft 33, as at 35, is a tube 36 adapted to pass through a hole let into the center of rotating disk 15 and to be firmly fixed to rotating disk 15 15 by rings 37. Firmly fixed to shaft 33 between bearings 32 and 34 is a toothed gear member 38. Engaging gear 38 is a rack 39 slidably mounted in brackets 40 and 41 mounted, respectively, on the under side of surface member 10 and the inside 20 of frame 11. Rack 39 is cut away as at 42 to allow free rotation of gear 38. A compression spring 43 is disposed around rack 39 between bracket 41 and a shoulder 44 fixed to rack 39. The rack 39 is actuated by any suitable means 25 such as a knob 45. Current is taken from transformer 26 to contact arms 21 by any suitable circuit electrically connected to bearing member 32 by the bolt 46. From the bearing member the current passes upward through shaft 33 to tube 30 36 and thence to rings 37 and outward therefrom through the junction 22 to the contact arms 21.

Figs. 9 and 10 show in section one embodiment of my novel past play indicating means which are secured to frame 11 by bolts 47 as shown in 35 Figs. 1 and 5. In Figs. 9 and 10, 48 represents a face plate for the past play indicator which is clamped against frame member 11 by the bolts 47. Carried by bolts 47 is back plate 49. Carried on bolts 47 between plates 48 and 49 is a 40 slab of insulating material 50 circularly bored through as at 51. Passing through plates 48 and 49 and suitably insulated therefrom and passing centrally through apertures 51 are shafts 52 which may be rotated by knobs 48. Securely 45 fixed to shafts 52 are metal disks 53, preferably of lead, designed to rotate in circular apertures 51 and out of contact therewith. Radially bored in metal disks 53 are chambers 54 designed to carry compression springs 55 and metal ball members 56 which are pressed against the walls of apertures 51 by the action of springs 55. Suitably mounted in the walls of apertures 51 are contact points 57 designed to engage ball members 56 when disks 53 are suitably rotated. It is to be 55 noted that the number of contacts 57 and the number of ball members 56 for each of disks 53 are chosen with respect to the play to be indicated by each as for instance there are three contacts 57 and three ball members 56 for the indicator designating balls, and two each for the indicators designating strikes and outs. Now with reference to Figs. 5 and 9 current is led to disks 53 by a suitable conduit 58 here shown as receiving current from transformer 26 through the 60 contact at 46 which was described above. Conduit 58 is electrically connected to shafts 52 by shoes 59 thereby energizing metal disks 53 and ball members 56. From contacts 57 suitable circuits 60 lead to lights 61 which in turn have a 65 common ground 62 here shown as connected to ground plate 28 to complete the several circuits. When in the course of play it is desired to indicate that one ball, strike, or out or any combination of these is to be scored against the batter, 70 75

the appropriate knob or knobs 18 are rotated and one or more of ball members 56 brought into contact with the appropriate contacts 57 thereby completing the circuit or circuits to the appropriate light or lights 61 illuminating the light or lights 61 and thereby recording the score against the batter. Contacts 57 and ball members 56 are so arranged with respect to each other in the several switch units that it is possible to score 10 any combination of balls, strikes, and outs that would occur in the actual playing of the game.

Mounted on frame 11 adjacent switch actuators 18 (Fig. 5) is switch mechanism 63 similar in construction to those described with reference to Figs. 9 and 10 and designed for use in indicating players on bases. With reference to Figs. 7 and 8 switch mechanism 63 comprises a face plate 64 and a rear plate 65 secured to frame 11 by bolts 66. Held between plates 64 and 65 and 20 mounted on bolts 66 is a slab of insulating material 67 circularly bored as at 68. Passing through plates 64 and 65 and suitably insulated therefrom and rotatable therein and passing centrally through recess 68 is shaft 69 designed 25 to be rotated by knob 70. Secured to shaft 69 and free to rotate within recess 68 is metal disk 71 which has four radial chambers 72 let therein as shown. Mounted in chambers 72 are compression springs 73 and ball members 74 designed 30 to be pressed against the walls of recess 68 by the action of springs 73. Suitably mounted in the walls of recess 68 are three contacts 75 designed to engage ball members 74 when disk 71 is suitably rotated. Current is led to disk 71 by conduit 35 76 which is electrically connected to conduit 58, above described, and electrically engaging shaft 69 through shoe 77. From contacts 75 circuits 78 lead to one filament in each of the lights 14 arranged on playing field 13 to represent 1st, 2nd, 40 and 3rd bases. It is now apparent that by appropriate rotation of disk 71 by knob 70 ball members 74 may be moved to engage contacts 75 and the circuits closed to appropriate lights 14 to designate men on bases in any combination 45 that may occur in the actual playing of the game.

Inspection of the circuit diagram of Fig. 5 will show that the lights 14 designed to indicate 1st, 2nd, and 3rd bases, and any combination of players thereon, are likewise used to indicate hits. 50 Thus if the disk 15 indicates a single, double, or triple, the lights at 1st, 2nd, or 3rd bases will light respectively. To the end of avoiding confusion each light 14 is a double filament light as shown in Fig. 6, one filament being less brilliant than the other and connected to show the position of the player on the base and the more brilliant filament being used to indicate the size of the hit, though the reverse in this use may be desirable.

With reference now to Fig. 2, mounted upon insulating medium 23 beneath disk 15 and adjacent contacts 20 is a semi-circular element 79 adjustably secured to insulating medium 23 by slotted arms 80 and screws 81. Mounted for rotation upon element 79 adjacent the dividing spaces between certain pairs of contacts 20 are a plurality of three-pointed chance elements 82 of conducting material designed to be rotated by contact arms 21 when disk 15 is spun. The 60 points or arms of chance elements 82 are adapted to pass over and in contact with the contacts 20 and are so spaced that it is possible for any two of the points to bridge the two adjacent contacts 20 if the chance element happens to 65 cease rotation with two of its points on these contacts.

Thus an additional element of chance is added to game. For instance, considering the chance element 82 nearest pointer 17 in Fig. 2, the contacts 20 adjacent this chance element are those respectively connected to the circuits for 5 the lights 14 on the game board designating "Bunt" and "Out". Therefore, if contact 21 stops after rotation upon the contact for "Bunt" and the chance element 82 stops rotation with two of its points bridging the contacts "Bunt" 10 and "Out", then the circuit to the "Out" light will be energized as well as that to the "Bunt" light and the "Bunt" play will be modified and the player considered as "Out". The same is true of all the other chance elements and an 15 increase in the number of plays afforded by the game is had. If, however, the players do not desire to use these additional chance elements 20 then screws 81 may be loosened and element 79 slid away from contacts 20 which acts to remove chance elements 82 from contacting position with adjacent contacts 20. Further, the use of the chance elements 82 affects the reading of the plays indicated on disk 15. As will be seen from Fig. 3, certain of the various plays 25 indicated on disk 15 are placed in pairs, each pair being separated by a dotted line. If after rotation of the disk but one light 14 on the board is illuminated (the situation arising when the contact 20 upon which the contact arm 21 30 comes to rest is not bridged by a chance element 82 with an adjacent contact 20) then the play on disk 15 opposite pointer 17 is alone read and combined with that indicated by the illuminated lamp to obtain the complete play to 35 be made. However, when two lights are illuminated after rotation of disk 15 (the situation when one of the chance elements 82 is bridging two adjacent contacts 20 on one of which the contact arm 21 is resting) then not 40 only the play indicated on disk 15 opposite pointer 17 but also the adjacent play on the other side of the dotted line are used to complement the play indicated by the lights.

Now let it be supposed that the game board 45 is in readiness for play. The transformer 26 is energized by current from outlet 25. The player grasps knob 45 and draws it away from frame 11 against the action of spring 43. At the same time rack 39 engages gear member 38. 50 Upon release of knob 45, spring 43 forces rack 39 inwardly and rapidly rotates gear member 38 which in turn, through shaft 33 and sleeve member 36, rapidly rotates disk 15. The rotation of disk 15 rotates contact arms 21 rapidly over 55 contact points 20 and arms 21 rotate chance elements 82 if they are in use. When rack 39 reaches its inward position, gear 38 rotates freely in the cut away portion 42 of the rack 39, the disk 15 and contact arms 21 continuing to rotate until brought to rest by friction. When disk 15 comes to rest, one of the plays indicated upon its face will lie opposite pointer 17. At the same time, one of contact arms 21 has come to rest on one of the contact points 20 closing 60 one or more circuits to bulbs 14. The bulbs 14 whose circuits are completed are then illuminated indicating what amplification, modification or clarification should be made of the play indicated by pointer 17, or vice versa. When the 65 indications of both the disk 15 and the lights 14 are combined, the player is advised as to the exact nature of the play to be made. The arrangement of the contact points 20 and that of the designations on the rotating disk 15 are such 70 75

that the plays indicated by the combination of the two designations correspond closely in both character and frequency of occurrence to the plays of an actual baseball game.

- 5 Now suppose disk 15 comes to rest with pointer 17 indicating "Strike", as shown at 83 (Fig. 3). The contact arm 21 then rests on contact point 20a (Figs. 2 and 5). The contact arm 21 then closes the circuit to the bulb 14 marked "Strike".
- 10 The player then rotates the appropriate knob 18 (Fig. 5) of the past play indicator so that one ball member 56 engages the first contact 51. The resulting illuminated light 61 indicates that one strike has been made. The same player 15 then rotates disk 15 again; this time it may stop so that pointer 17 indicates "Doubled to left field", as shown at 84 (Fig. 3). Contact arms 21 then rest on contact point 20b (Figs. 2 and 5) which close the circuit to light 14 marked "2nd" 20 and "Double". The play as then indicated by disk 15 and light 14 is that the batter doubled. The player would then rotate knob 70 of the switch mechanism 63 until the lower left-hand ball member 14 in Fig. 8 engaged the contact 75 25 for the circuit to the other filament of the light 14 at 2nd base. This circuit would then be closed and the lamp would show two degrees of light to indicate a runner on 2nd base as well as the fact that the runner had doubled. The 30 circuit to the "double" filament of this light would of course be opened immediately upon further rotation of disk 15 by the next player.
- The first player having finished his turn at bat the next player rotates disk 15 and suppose 35 disk 15 stops with the play "Bunt along 3rd B. line" as indicated at 85 (Fig. 3) opposite pointer 17. Then contact arm 21 comes to rest on contact 20c (Figs. 2 and 5) and closes the circuit to the light 14 marked "Bunt". But here the chance 40 element 82 adjacent contact 20c may come into play. If this chance element comes to rest with one point on contact 20c and another point on contact 20d then not only will the circuit to the light 14 marked "Bunt" be closed but also the 45 circuit to the light 14 marked "Error". Therefore, when disk 15 comes to rest two lights on the game board will be illuminated and, as described above, both of the plays in the pair must be read to complete the play. Thus in this instance as 50 the lights "Bunt" and "Error" have both lighted, not only the play designation "Bunt along 3rd B. line" on the disk must be used, but also the other play in the pair "Bunt fumbled by pitcher", the result being that the complete play is properly 55 scored by charging the pitcher with an error and rotating knob 70 to indicate a man on first. Thus a combination of plays is possible with the use of chance elements 82 whereas but one play would be had if not used.
- 60 One or more persons can play the game as above described. It is preferable to have the players divided into two teams as in an actual game of baseball. If two teams are playing, the players of one team play in rotation, each player 65 spinning the disk until he is either out or on base, and until the team has acquired three outs when the other team has its turn at play, the succession of players and teams being identical to that practiced in the actual game.
- 70 There are various modifications of the above 75 described game which will now occur to those who are skilled in the art and which may be made without departing from the spirit of the invention. For instance, counters or players may be used upon the reproduction of the baseball dia-

mond on the game board to indicate the players on base or for other purposes. It also is obvious that the game mechanism disclosed may be quickly and easily converted to the playing of games other than baseball, such as mushball or soft- 5 ball, by merely substituting for the rotating disk shown a disk bearing upon its surface indications of the plays possible in mushball or soft-ball. Further, by appropriate rearrangement of the reproduction of the playing field and the lights 10 thereon, and by utilizing a rotating disk bearing appropriate plays, such other games as football can be played upon the above described device. To determine the scope of the present invention reference must therefore be had to the appended 15 claims.

This application is a continuation in part of my application, Serial Number 92,854 filed July 27, 1936.

What is claimed is:

1. In a game board apparatus of the type described, a game board, a rotatable disk mounted on said board bearing on its surface a plurality of designations of plays of the game, a plurality of electric lamps mounted upon said game board 25 and associated with play designations complementary to those appearing on said disk, circuits for said lamps, contacts for said circuits beneath said disk on said board, contact arms carried by said disk to engage said contacts and close said 30 circuits, and a plurality of rotatable elements actuated by said contact arms and adapted when at rest in certain positions to bridge certain pairs of said contacts.

2. In a game board apparatus of the type de- 35 scribed having a game board with a play bearing rotatable disk mounted on its surface and electric lamps to indicate plays complementary to those appearing on said disk, means carried by said board and rotated by said disk to at random 40 bridge pairs of said lamps to modify the play that would be otherwise indicated by the at rest position of said disk.

3. In a game board apparatus of the type de- 45 scribed, a game board, a rotatable disk on said board having on its surface a plurality of designations of plays of the game, a plurality of lamps on said board associated with play designations complementary to those appearing on said disk, circuits for said lamps, contacts for said circuits 50 on said board beneath said disk, contact arms carried by said disk to engage said contacts and close said circuits, and a plurality of three armed rotors carried by said board adjacent certain pairs of said contacts and adapted to be rotated by said 55 contact arms, each of said rotors being so constructed and arranged that upon rotation the arms thereof pass over and in contact with the two contacts of the particular pair associated therewith, whereby when said rotor comes to rest 60 with its arms bridging said two contacts the lamps in circuit with both contacts will be illuminated should one of the contact arms carried by said disk come to rest upon either of the bridged contacts.

4. In a game board apparatus of the type de- 65 scribed, a game board, a disk rotatably mounted with respect to said game board and bearing upon its upper surface a plurality of circumferentially disposed designations of various plays of the 70 game, means fixed with respect to said game board for indicating the play designation of said disk to be used, a plurality of lamps carried by said game board also associated with designations of various plays of the game, a plurality of con- 75

tact elements electrically connected with said lamps and carried by said game board beneath said disk, and a plurality of contact arms carried by said disk and adapted to close the circuits 5 through said lamps by engagement with said contact elements, the play designations on said disk, the contact arms carried thereby and the contact elements connected to said lamps being so arranged that the play indicated by the lamp or 10 lamps illuminated when the disk is at rest in any given position and that designated on said disk by the indicating means are mutually complementary and when combined define the proper play to be made by the player of the game.

15 5. In a game board of the type described, a surface member, a reproduction of a playing field upon said surface member, a rotatable disk mounted on said surface member adjacent said playing field, said disk bearing on its face a plurality of circumferentially disposed designations 20 of the plays possible in an actual game, an index mounted on said surface member adjacent said disk for indicating the play designation to be used when said disk comes to rest after having been 25 rotated, means for rotating said disk, a plurality of lights arranged about said playing field and associated with play designations complementary to the plays designated by said index and disk, circuits for said lights, contact points for said 30 circuits carried by said surface member beneath said rotatable disk, said contacts being arranged to partially cover the circumference of said disk, and a plurality of contact arms carried by said disk to engage said contacts and successively close 35 said circuits upon rotation of said disk.

6. In a game board of the type described, a surface member, a reproduction of a playing field upon said surface member, a rotatable disk mounted on said surface member adjacent said 40 playing field, said disk bearing on its face a plurality of circumferentially disposed designations of the plays possible in an actual game, an index mounted on said surface member adjacent said disk for indicating the play designation to be 45 used when said disk comes to rest after having been rotated, means for rotating said disk, a plurality of lights arranged about said playing field and associated with play designations complementary to the plays designated by said index 50 and disk, circuits for said lights, contact points for said circuits carried by said surface member beneath said rotatable disk, said contacts being arranged to cover only half of the circumference of said disk, and a pair of diametrically opposed 55 contact arms carried by said disk to engage said

contacts and successively close said circuits upon rotation of said disk.

7. In a game board apparatus of the type described, a game board, a disk rotatably mounted with respect to said game board and bearing upon its upper surface a plurality of circumferentially disposed designations of various plays of the game, means fixed with respect to said game board for indicating the play designation of said disk to be used, a plurality of lamps carried by said game board also associated with designations of various plays of the game, a plurality of contact elements electrically connected with said lamps and carried by said game board beneath said disk, a plurality of contact arms carried by said disk and adapted to close the circuits through said lamps by engagement with said contact elements, and means actuated by the movement of said contact arms in an unpredictable manner for bridging certain of said contact elements so as to close the circuits to more than one of said lamps should one of said contact arms come to rest on one of the bridged contacts, the play designations on said disk, the contact arms carried thereby and the contact elements 25 connected to said lamps being so arranged that the play indicated by the lamp or lamps illuminated when the disk is at rest in any given position and that designated on said disk by the indicating means are mutually complementary 30 and when combined define the proper play to be made by the player of the game.

8. In a game board apparatus of the type adapted for playing a game of baseball, a game board having upon its upper surface a representation of a baseball playing field, lamps carried by said game board including three indicating the positions of first, second and third bases, each of said three lamps having two filaments, a disk rotatably mounted on said game board and adapted to indicate by the position in which it comes to rest certain plays of the game, a plurality of contact members carried by said game board beneath said disk including three each of which is electrically connected to one of the filaments of one of said three lamps, means carried by said disk for engaging said contact elements and closing the electrical circuits through the said three filaments connected to the latter to indicate one, two and three base hits, and a selectively operable switch having three fixed contacts each electrically connected to one of the other filaments of said three lamps for indicating the presence of men on bases.

LAWRENCE QUINN. 55
